UNITED STATES PATENT OFFICE.

CHARLES A. OLSEN, OF PITTSBURG, PENNSYLVANIA.

TROLLEY.

SPECIFICATION forming part of Letters Patent No. 724,927, dated April 7, 1903.

Application filed December 24, 1902. Serial No. 136,452. (No model.)

To all whom it may concern:

Be it known that I, CHARLES A. OLSEN, a citizen of the United States of America, residing at Pittsburg, in the county of Allegheny and State of Pennsylvania, have invented certain new and useful Improvements in Trolleys, of which the following is a specification, reference being had therein to the accompanying drawings.

10 This invention relates to certain new and useful improvements in trolleys, and relates more particularly to that class that will retain a constant contact with the trolley-wire.

15 The present invention relates to that class of trolley-poles wherein an electric circuit is established and maintained between the stationary trolley-wire and the motors arranged in the moving car.

20 My invention further contemplates to provide a pole that will be extremely simple, strong, durable, comparatively inexpensive to manufacture, and highly efficient in its use.

25 With the above and other objects in view the invention consists in the novel construction, combination, and arrangement of parts to be hereinafter more fully described, and specifically pointed out in the claim.

30 In describing the invention in detail reference is had to the accompanying drawings, forming a part of this specification, and wherein like numerals of reference indicate like parts throughout the several views, in which—

35 Figure 1 is a side elevation of my improved trolley-pole, partly in section. Fig. 2 is a similar view more clearly illustrating the operation of the pole. Fig. 3 is an enlarged side elevation, partly in section, of the joint.

40 In the drawings the reference-numeral 1 indicates one section of the trolley-pole, and the upper section is represented by the reference-numeral 2. Between said sections is formed a knuckle-joint 3, which comprises two members having screw-threaded shanks adapted to be received in the sections of the trolley-pole.

45 A hanger 4 is rigidly secured at 5 to the upper section 2 of the trolley-pole, said hanger carrying an eye 6, to which is secured the coil-spring 7, which extends downwardly and

is connected to the eyebolt 8. The square 50 body portion of said eyebolt extends through the guide 9, which is rigidly secured to the trolley-pole section 1. The threaded portion 10 of the eyebolt extends through the bracket 11, which element is also rigidly secured to 55 the section of the pole 1, and an adjusting-nut 12 is secured upon the end of the threaded portion of the eyebolt, and a jam-nut 14 is also secured upon the threaded portion, as shown in Figs. 1 and 2 of the drawings. This 60 latter construction permits the adjustment of the eyebolt for the purpose of increasing and diminishing the tension of the coil-spring 11. An auxiliary spring 15 is arranged to the sections of the joint 3, said spring being preferably 65 a retractile spring having its free ends formed into hook portions, which are adapted to be seated in suitable recesses formed in the extensions 16 of the joint members, as clearly illustrated in Fig. 3 of the drawings.

70 The reference-numeral 17 indicates the trolley-harp, and 18 the trolley-wheel, which are of the ordinary and well-known construction. The trolley-wire is represented by the numeral 19.

75 It is a well-known fact that trolley-wheels are often displaced on account of the varying distance between the car and the trolley-wire, and by this device, as heretofore described, I have provided the compensating or yielding connection, which will accommodate itself to the various distances between the car and the trolley-wire and will effectually at all times form an electric contact with the wire and prevent the displacement of the wheel, 85 as is usual with the ordinary trolley-pole now in use.

80 Particular attention is directed to the fact that the device may be used with a single spring, such as 7, or the spring 15; but in actual practice I have found it advantageous to employ both springs, as a more yielding connection is established thereby.

85 It will be noted that various changes may be made in the details of construction without departing from the general spirit of my invention.

90 Having fully described my invention, what

I claim as new, and desire to secure by Letters Patent, is—

A trolley-pole formed of two sections, a knuckle-joint connecting said sections, recessed extensions carried by the members of said joint and a spring having hooked ends arranged in the recesses of the said extensions.

In testimony whereof I affix my signature in the presence of two witnesses.

CHARLES A. OLSEN.
